UNITED STATES PATENT OFFICE.

ANTON POPPER AND LEOPOLD ADELHOFER, OF NEW YORK, N. Y.

SEWING-MACHINE SUPPORTING AND DRIVING DEVICE.

Application filed July 16, 1921. Serial No. 485,158.

To all whom it may concern:

Be it known that we, ANTON POPPER and LEOPOLD ADELHOFER, citizens of the United States and Hungary, respectively, and residents of the city of New York, in the county of New York and State of New York, have invented certain new and useful Improvements in Sewing-Machine Supporting and Driving Devices, of which the following is 10 a specification.

The present invention relates to a device for supporting and driving sewing machines.

Machines for operating on hats and other articles which are adapted to be placed over the front end of the machine head during the sewing operation must be supported in such position in relation to the work table to permit of a convenient handling of the 15 work during the sewing operation. It has been proposed heretofore to use ordinary or low base sewing machines for this class of work, by mounting the same upon a support on the machine table, said support carrying 20 a driven shaft for engagement with the machine on the support. Difficulties have been experienced with this construction for the reason that the clutch member of the driven shaft does not fit all makes and types of 25 sewing-machines, the result being that the support is limited in its use.

The main object of the present invention is to so construct the support that it may be associated with all types of sewing-machines 30 and also with different makes, thereby rendering its use universal.

Another object of the invention is to produce a support of the character mentioned which is simple in construction, efficient in 35 operation and capable of manufacture on a commercial scale, or in other words one which is not so difficult to make as to be beyond the reasonable cost of such a contrivance.

40 With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended

claim, without departing from the spirit or sacrificing any of the advantages of the invention.

One of the many possible embodiments of the invention is illustrated in the accompanying drawings, in which:

Figure 1 is a front elevation of a sewing-machine mounted on a supporting device constructed in accordance with the present invention; and Fig. 2 is a section taken 65 on line 2—2 of Fig. 1.

In the drawings the numeral 10 indicates a sewing-machine table, provided with an opening 11 of a size to permit of a convenient handling of the work being sewn on the machine adjacent the same. The sewing-machine head, denoted by the numeral 12, is detachably mounted, in a manner hereinafter to be described, on a support 13, the latter being fixed in any suitable manner to 70 the table 10. The support comprises a base 14 of any suitable construction, from which rises a sewing-machine supporting bed 15. This bed projects laterally on one side beyond the base 14 over the opening 11, so as 75 to support the machine in an overhanging position above said opening, whereby an unobstructed space may be provided for the manipulation of the work on the machine.

In the longitudinal center line of the supporting bed 15 there is formed a row of holes 16, into one of which fits a lug 17, projecting down from the underface of the base 18 of the sewing-machine head, while through another one of these holes extends 80 a screw-threaded bolt 19 on the sewing-machine head. With the threads of this bolt mesh those of a nut 20, that abuts against the underface of the bed 15, as clearly 85 shown in Fig. 1 of the drawings. There are more than two holes provided in the bed 15 to permit the mounting thereon of sewing-machine heads of different kinds and sizes.

On the support 13 are provided two bearings 21, said bearings being in alignment and disposed in the longitudinal axis of the base of the said support. In these bearings is rotatably mounted a counter-shaft 22, to which are fixed two pulleys, denoted by the numerals 23 and 24. These pulleys are adjustable longitudinally on the said shaft, set-screws 25 serving to hold the same in any adjusted position. To permit the set-screws 100 to properly grip the shaft, the latter is some- 105

what flattened longitudinally at the places indicated by the numerals 26 and 27, the set-screw of the pulley 23 co-operating with the flattened section 26 of the shaft and the 5 set-screw of the pulley 24 with the flattened section 27 thereof. The pulley 23 is mounted in alignment with the pulley 28 of the machine head, a belt 29 running over the pulleys 23 and 28. The pulley 24, on the 10 other hand, is mounted in alignment with a power transmitter 30 of any suitable type, depending from the underface of the table 10. Over this power transmitter and the pulley 24 runs a belt 31. The power transmitter includes a stepped pulley, and it is for this reason that the pulley 24 must be 15 adjustably mounted upon the counter shaft 22, the latter being driven at various speeds according to the type of the machine operated thereby.

Inasmuch as all sewing-machine heads are provided with a driven pulley 28 and since the pulley 23 on the counter shaft 22 is adjustable longitudinally on the said counter-shaft, it is obvious that the supporting and 25 driving device is capable of use with sewing-machines of all types and sizes, the only connection between the sewing-machine head and the said device being constituted by the 30 belt 29. All that is necessary to adjust the supporting and driving device to a machine is to shift the pulley 23 into alignment with the driven pulley of the machine head and put the belt 29 in place. The pulley 24 is 35 shifted only in case the machine is to run at a speed different from that of the one

that had been previously mounted on the supporting bed 15.

What we claim is:—

The combination with a work table, of a support thereon comprising a base and a bed rising from said base laterally projecting therefrom, said bed being provided with a plurality of holes arranged in a row, a sewing machine head on said bed including 40 a driven pulley, a lug projecting down from the base of said sewing machine head into one of said holes, a screw-threaded bolt on said sewing machine head extending through another one of said holes, whereby the position of said sewing machine head on said bed may be varied, a counter-shaft rotatably mounted on said support above its base, a pulley on said counter-shaft in alignment 45 with said driven pulley, a belt running over said pulleys, a second pulley on said counter-shaft, a power transmitter including a pulley depending from the underface of said table, a belt running over the second pulley on the counter-shaft and the pulley on said 50 transmitter, the shaft of said driven pulley and the shaft of said power transmitter pulley extending in parallel relation to said counter-shaft, both pulleys on said counter-shaft being adjustable longitudinally 55 thereon.

Signed at New York, in the county of New York and State of New York, this 7th day of June, A. D. 1921.

ANTON POPPER.
LEOPOLD ADELHOFER,
